US0D1101701S

(12) **United States Design Patent** (10) **Patent No.:** **US D1,101,701 S**
(45) **Date of Patent:** **** Nov. 11, 2025**

(54) **CONNECTOR**(71) Applicant: **F&V Corporation**, North Royalton, OH (US)(72) Inventors: **Ryan Alan Lally Fry**, North Royalton, OH (US); **James Charles Varner**, Independence, OH (US); **Xianyong Nie**, Donguang (CN)(73) Assignee: **F&V Corporation**, North Royalton, OH (US)(**) Term: **15 Years**(21) Appl. No.: **29/878,519**(22) Filed: **Jun. 23, 2023**(51) LOC (15) Cl. **14-02**

(52) U.S. Cl.

(57) **CLAIM**

The ornamental design for a connector as shown and described.

DESCRIPTION

FIG. 1 is a top perspective view of a connector showing our new design;

FIG. 2 is a bottom perspective view thereof;

FIG. 3 is a side view thereof;

FIG. 4 is a top view thereof; and,

FIG. 5 is a bottom view thereof.

The broken lines in the drawings are included to show portions of the connector that form no part of the claimed design.

1 Claim, 2 Drawing Sheets
